(57) **CLAIM**

The ornamental design for an axle toy brick as shown and described.

DESCRIPTION

FIG. 1 is a top perspective view of an axle toy brick.

FIG. 2 is a bottom perspective view of the axle toy brick.

FIG. 3 is a second, top perspective view of the axle toy brick.

FIG. 4 is a second, bottom perspective view of the axle toy brick.

FIG. 5 is a side plan view of the axle toy brick.

FIG. 6 is a second, side plan view of the axle toy brick.

FIG. 7 is a front plan view of the axle toy brick.

FIG. 8 is a back plan view of the axle toy brick.

FIG. 9 is a top plan view of the axle toy brick.

FIG. 10 is a bottom plan view of the axle toy brick.

FIG. 11 is a top perspective view of a second embodiment of the axle toy brick.

FIG. 12 is a bottom perspective view of the second embodiment of the axle toy brick.

FIG. 13 is a second, top perspective view of the second embodiment of the axle toy brick.

FIG. 14 is a second, bottom perspective view of the second embodiment of the axle toy brick.

FIG. 15 is a side plan view of the second embodiment of the axle toy brick.

FIG. 16 is a second, side plan view of the second embodiment of the axle toy brick.

FIG. 17 is a front plan view of the second embodiment of the axle toy brick.

FIG. 18 is a back plan view of the second embodiment of the axle toy brick.

FIG. 19 is a top plan view of the second embodiment of the axle toy brick; and,

FIG. 20 is a bottom plan view of the second embodiment of the axle toy brick.

The broken lines in the figures show features of the axle toy brick that form no part of the claimed design.
